UNITED STATES PATENT OFFICE.

JOHN E. CHAMBERS, OF SHELBYVILLE, INDIANA, ASSIGNOR TO CHAMBERS MAN'FG CO., OF SHELBYVILLE, INDIANA, A CORPORATION OF INDIANA.

FIRELESS COOKER.

1,389,813.

Specification of Letters Patent. Patented Sept. 6, 1921.

Application filed October 31, 1917. Serial No. 199,506.

To all whom it may concern:

Be it known that I, JOHN E. CHAMBERS, citizen of the United States, residing at Shelbyville, in the county of Shelby and 5 State of Indiana, have invented certain new and useful Improvements in Fireless Cookers, of which the following is a specification, reference being had therein to the accompanying drawing.

10 This invention relates to fireless cookers, and is designed primarily for use in connection with rolling kitchens or the like, the cooker being of such construction, however, that it is equally serviceable and useful for 15 field or trench service, as well as in hotels, restaurants or other institutions.

The invention has reference to that type 20 of fireless cooker wherein is employed a casing having non-conducting walls forming an interior cooking chamber adapted to receive a cooking vessel, and associated means for imparting the necessary heat to the chamber and surrounding walls, whereby when the chamber is sealed the confined heat will 25 continue to cook the material contained in the vessel, after the heat supplying medium has been removed or cut off, and it is one of the objects of the invention to provide an improved device of this character, simple and 30 neat in design and construction, of but few parts, comparatively inexpensive to produce, light, but strong and durable in character, highly efficient and satisfactory in service, and to otherwise generally improve upon 35 structures of this type.

One of the features of the invention resides in a novel and improved construction of surrounding walls or casing for the cooker with a view of strengthening the 40 same, and at the same time reducing the weight thereof whereby the same may be readily handled and repositioned as desired.

Another object of the invention is to provide in a cooker of the character under consideration, a movable door to facilitate the entrance into, or removal from, the cooker, of a heat transmitting medium, and to provide for the necessary draft, together with means of novel and improved construction for securing the door in place and in tight engage-

ment with the surrounding wall of the casing.

It is a further object of the invention to provide a novel and improved means for supporting within the cooker, a cooking vessel proper, and efficient means for facilitating the passage of the heated products of combustion around the cooking vessel and out of the cooker as desired.

The invention further contemplates novel 60 and improved means for closing the upper end of the cooker, said means preferably taking the form of a hingedly connected covering, and having associated means for locking the same in a lowered position or in 65 sealed contact with the body of the cooker.

Further, the invention includes means for maintaining the cover or top wall of the cooker in a slightly open position to allow 70 the products of combustion to escape, while at the same time retaining considerable of the heat elements, together with means for maintaining the cover in an entirely open position.

The invention still further includes means 75 whereby a portable heat transmitting element may be positioned within the cooker, and associated means for guiding and accurately positioning the heat transmitting element in the assembling of the latter, said 80 last mentioned means preferably taking the form of a diaphragm arranged below the cooking vessel and above the body or fluid containing part of the heat transmitting element.

Still other and further improvements, and 85 novel details in the construction and arrangement of the various parts of the apparatus will be appreciated from the description to follow, which, for a clear understanding of the invention is to be considered 90 in connection with the accompanying drawings, which form a part hereof and wherein is disclosed for the purpose of illustrating a convenient and satisfactory embodiment of 95 the invention.

In the drawings:

Figure 1 is a front elevation of a cooker embodying my improvements.

Fig. 2 is a top plan of the same.

Fig. 3 is a vertical section with the cover in slightly raised position.

Fig. 4 is a perspective detail enlarged of a retaining means for the cover.

Fig. 5 is a horizontal section substantially on the line 5—5 of Fig. 1.

Fig. 6 is a top plan of the cooker with the cover removed.

Fig. 7 is a vertical section of the cooker with the cover in lowered position and illustrating by dotted lines the cover in raised position as well as means for maintaining the same in this position.

Fig. 8 is a detail, with parts broken away, of a means for locking the cover in elevated position.

With more particular reference to the drawings, wherein like reference numerals refer to corresponding parts throughout the several views, 1 and 2 are inner and outer walls respectively, of the casing constituting the side walls or body part of the cooker. These walls may take different formations, but in the illustrative embodiment of the invention are conveniently cylindrical in form and constructed of sheet metal, whereby to reduce the weight of the apparatus as a whole as well as to conserve expense. These walls, 1 and 2, have reinforcing collars or circular members, the one, 3 being positioned at the upper end thereof and the other, 4 at the lower end thereof. These collars are preferably reinforcing material such as channel castings, the flanges of which rest between and engage the opposed surfaces of the walls 1 and 2, thereby spacing these walls and strengthening the same at the ends. Interposed between the walls 1 and 2 and the collars 3 and 4 is a suitable filling of heat insulating material 5. The parts just described constitute the body of a cooker, which may, if desired be devoid of the usual bottom, and the lower collar 4 constituting a base may have an outwardly projecting flange or flanges 5^a, apertured to receive securing bolts or the like, whereby to secure the casing directly upon the floor of the truck or room as the case may be, which said floor will constitute the base of the cooker. In this connection if desired, of course a suitable plate may be secured to the cooker at the base thereof or interposed between the same and the flooring, but in practice, I have found it of advantage to dispense with a connected base, which reduces the cost of production, as well as the weight of the apparatus.

Various means may be provided for transmitting heat to the interior of the cooker, that means which is preferred being of independent source and conveniently taking the form of a gasoline fire pot or torch and including a container part 6, a burner 7 and a connecting stem or conduit 8.

It is desirable to remove the heating ele-

ment after the container has transmitted to it the desired temperature, and to this end, and also to provide the necessary air while the heater is in operation, a movable door in the side wall, preferably at the front of the container is provided, the said door comprising an outer wall 9 preferably curved to conform with the curvature of the outer wall 2 of the body part of the casing, and an inner wall 10 conveniently having an offset part 11 forming an abutment and connected in any desired manner with the front wall 9. Interposed between the walls 9 and 10 of the front door is suitable heating insulating material. In the preferred embodiment of the invention this door is bodily removable. In order to accommodate the removable door the front wall of the casing is provided with an opening 12, and conveniently the inner wall 1 of the casing has offset flanges 13 forming a collar inclosing the heat insulating material surrounding the opening 12. The flange or collar portion 13 has returned bent parts 14 which overlie the outer surface of the outer wall 2 of the casing and being free at the edges and slightly spaced from the said outer surface of the wall 2 of the casing is free to slightly yield upon itself and form in effect a packing interposed between the body of the casing and the removable door. When the door is in closed position the body portion 14 thereof will substantially fill this space provided by the opening 12, the abutments or shoulders 11 contacting with the flanges 13 surrounding said opening, and the outer wall 12 of the door overlying the outer wall 2 of the casing as well as the yieldable flanges 14 just described. A preferred means for locking the door in closed position conveniently takes the form of opposed locking arms or bars 15 pivoted at one end 16 in any desired manner to the front wall 9 of the door adjacent the opposite sides thereof and terminating in finger engaging parts 17. These bars are slightly yieldable longitudinally and are adapted to engage behind the offset flanges 18 of lugs secured to the front wall of the casing one adjacent each side of the door opening.

In order to separate the container 6 from the burner part of the heat transmitting element and further to accurately guide the same in the positioning of the latter there is provided a diaphragm 20, conveniently constructed of outer sheets of metal and an intermediate sheet of heat insulating material. The diaphragm 20 has therein an elongated slotted way 21 forming a suitable guide to facilitate the positioning and removal of the heating element. The slot is preferably of such a length that when the flue or stem 8 of the heating element which engages within the slot reaches the limit of its movement in the slot the burner will be

accurately positioned centrally beneath the cooking vessel, whereby to equally distribute the heat products.

- The cooking vessel proper is indicated at 5 22, the same preferably having a cylindrical wall of slightly less diameter than that of the surrounding wall 1 whereby to provide an annular passage way 23 for the passage of air and products of combustion. The 10 cooking vessel is freely suspended within the casing, and is preferably entirely supported at the upper end thereof through the medium of a circumferential flange or bead 24 at the upper end of the vessel 22 adapted 15 to rest upon an inwardly projecting flange or flanges 25 conveniently integral with the upper collar or ring 3 of the cooker casing. The supporting flange 25 for the cooking vessel is provided with one or more air passages 20 for the escape of the air and products of combustion, and these air passages are conveniently formed by cut out parts 26 in the flange 25. In the preferred construction the supporting flange 25 takes the form of 25 segmental parts separated from one another by segmental slots forming the air passages 26 as more particularly illustrated in Fig. 6 of the drawings. The cooking vessel is preferably provided with a removable lid 27 conveniently formed of thin sheet metal and having a flange 28 to engage the inner surface of the side wall of the vessel. The lid 27 has a centrally dished part 29 and a flat handle part 30 bridging the space formed by the dished part, and said handle is in horizontal alignment with the outer surface of the lid 27 whereby to offer no obstruction thereabove.
- The cover for the cooker includes a collar 40 or ring 31 conveniently of channel iron, the flat part of which is adapted to engage the upper flat surface of the collar 3 of the body part of the cooker. The inner wall of the cover is formed of sheet metal 33, the 45 same having a depending annular flange adapted to engage the inner edge of the collar 31, the wall 33 of the cover forming with said flanged part an annular recess or chamber to receive the supporting flange 50 25 of the ring 3 and the upper edge of the cooking vessel mounted upon said flange. The outer wall 34 of the cover is also preferably formed of sheet metal and has a downwardly projecting flange 35 adapted 55 to rest upon a shouldered portion 36 in the outer edge of the collar 31. Interposed between the walls 33 and 34 of the cover is a filling of suitable heat insulating material 37.
- 60 The cover is preferably hingedly connected to the body part of the casing through the medium of registering apertured lugs 38 and 39 on the collars 3 and 31 respectively, and a bolt or pintle 39^a fitted in said apertures 65 and having terminal nuts or heads, 40. The

collar or ring 31 has at the front thereof a U-shaped projection 41 forming a handle whereby the cover may be raised or lowered at will.

The preferred means for retaining the 70 cover in closed or slightly elevated position is preferably constructed as follows:

Projecting outwardly from the ring 3 of the casing is an apertured lug 42 adapted to receive a stem 43 projecting downwardly 75 from the retaining member proper 44. The member 44 is adapted to have oscillating movement, through the medium of the loose engagement of its stem 43 in the recess of the fixed lug 42. The retaining member has 80 a recessed part 45 adapted in one position of the member to engage over the handle 41 when the cover is in sealed contact with the top edge of the casing. The cover will be thereby retained in closed position. Now 85 assuming that it is desired to retain the cover in slightly open position whereby to permit the products of combustion to escape and at the same time retain the majority of the heat, the retaining member 44 is ro- 90 tated about its pivotal connection in a reverse direction whereby the shoulder portion 46 thereof will engage between the rings 31 and 3, thereby retaining the cover in spaced relation to the body portion of the 95 cooker at the front edge thereof and providing a free escape for the vapors and gases. The retaining member may be locked in its different positions through the medium of a thumb nut 47 having threaded engagement with the lower end of the pintle 43.

Suitable means may be provided for maintaining the cover in completely opened or raised position, and this means, as illustrated takes the form of projecting lugs 49 and 105 50 spaced vertically from one another and suitably supported upon the frame work 51 of the truck, or wall of the room according to the use to which the invention is put. The lugs 49 and 50 are adapted to engage 110 over opposite edges to the hand engaging part of the handle 41, and when in this position a locking bolt 52 is adapted to engage in registering apertures in the lugs 49 and 50 and overlie the said hand engaging part 115 whereby to lock the cover in raised position. The retaining bolt 52 may be held in a convenient position for use through the medium of a chain or the like 53.

It is believed that the construction and 120 operation of the apparatus will be appreciated from the description above, likewise the advantages resultant therefrom, but these may be briefly reviewed as follows:

The cooker is primarily designed for use 125 in trucks preferably motor trucks in army service, though it is understood that the same is equally useful in other connections, and it will be appreciated that when in use upon trucks gasoline fuel for the stove is 130

quite desirable, since gasoline is always carried by such trucks, and under operative conditions the consumption of fuel is exceedingly inexpensive. Assuming that it is desirable to cook articles or material within the vessel 22, the heat transmitting medium such as a gasoline torch stove is inserted in the cooker, the slotted way 21 constituting a guide for positioning the stove, and the burner being ignited. When the fire is burning beneath the cooking vessel, the insulated cover of the container should be nearly closed, and the retaining member 44 is therefore placed in position to constitute an abutment for limiting the closing movement of the cover. In order to burn properly there must be an upward draft or outlet for the products of combustion, and the front door 9 being open or removed, the products of combustion will readily pass between the inside wall 1 of the cooker and the wall of the cooking vessel, thereby conveying heat to the latter, the products of combustion finding an escape through the openings 26 formed by the segmental flanges which support the bead at the upper end of the cooking vessel. The cover when in slightly raised position will tend to restrict the outlet of the heat elements and a considerable amount of heat will be retained by the cover. The openings 26 will be entirely closed, however, and the draft stopped so soon as the cover is closed.

It will be understood that the opening 12 in the lower part of the cooker will be always left open when the fire is on. When the contents of the cooking vessel have been sufficiently heated, the fire pot is removed, the lower door 9 closed, and the retaining member 44 rotated so as to be positioned out of the path of the cover which will permit the latter to be entirely closed in which event there will be no escape of heat and no burners inside of the cooker containing pressure or consumed fuel to cause soot or explosive gases.

In view of the fact that the use of the fire is but for a comparatively short time, while the cooking may proceed for hours after the fire pot is removed, this arrangement permits of the use of the fire pot and burner for other cooking purposes. The independent source of heat is further peculiarly adapted to military services in that it requires no pipe lines or complicated construction and it is readily understood and interchangeable at will.

The diaphragm 20 positioned below the cooking vessel is the two fold function of protecting the gasoline tank 6 from the heat of the burner, and second to accurately locate the fire pot relative to the center of the cooking vessel.

What I claim is:

65 1. In a fireless cooker, the combination of

a casing, comprising inner and outer side walls with an interposed packing of insulating material, a top comprising inner and outer walls and an interposed packing of insulating material, said top being hingedly connected to the side walls, so as to permit of access to the interior of the cooking chamber formed by said walls, a cooking vessel suspended from a point adjacent the top of the side walls, a fuel supply tank and burner adapted to be positioned below the cooking vessel and to be bodily removed as a unit, said side walls having a front opening for such removal, and a bodily removable door having an interior heat insulating material, 70 said door having a flange to engage the wall surrounding the front opening of the casing, and means for normally retaining said door in tight engagement with the casing, comprising spring arms pivoted one adjacent 75 each side of the door at the front thereof, and lugs on the front wall of the casing adapted in the swinging movement of said arms to be engaged by the latter and thereby exert spring pressure on the door. 90

2. In a fireless cooker, the combination of a body part comprising inner and outer tubular walls having an interposed filling of heat insulating material, and open end walls comprising collars fitted to the inner and outer walls at the ends thereof, one collar having means to support a cooking vessel positioned in the chamber formed by said walls, heat creating means arranged within said chamber below the cooking vessel, the body part of the cooker having an opening at a point adjacent the lower end thereof in one of its sides, a closure for said opening, the said heat creating means being bodily removable as a complete unit through said opening and when in position adapted to rest on the supporting surface for the cooker and a movable closure for the upper end of said chamber. 100

3. In a fireless cooker, the combination of a body part comprising inner and outer tubular walls having an interposed filling of heat insulating material, and open end walls comprising collars fitted to the inner and outer walls at the ends thereof, the lower collar being adapted to rest upon a suitable supporting surface which said surface constitutes a base for the cooker, and one collar having means to support a cooking vessel positioned in the chamber formed by said walls, heat creating means arranged within said chamber below the cooking vessel, said heat creating means adapted to rest directly upon the supporting surface and be inclosed by the side walls of the cooker, and being bodily removable at will a movable closure 110 for the upper end of said chamber, the supporting means for the cooking vessel having air openings, and the tubular wall of the cooker having an air inlet part adjacent the base thereof. 115

4. In a fireless cooker, the combination of a cylindrical body part comprising concentric walls of sheet metal separated from one another by a filling of heat insulating material, reinforcing collars interposed between said cylindrical walls at the ends thereof, the lower collar being adapted to rest upon a supporting surface for the cooker and forming a surrounding wall for an open bottom end for the cooker, a heat insulated cover hingedly connected to the upper collar, and said upper collar having an inwardly projecting flange, bodily removable heating means positioned within the body part of the cooker and projecting through the open bottom thereof to rest upon the supporting surface therefor and a cooking vessel arranged above the heating means and having a flange at the upper edge thereof adapted to engage said flange of the upper collar.
5. In a fireless cooker, the combination of a cylindrical body part comprising concentric walls of sheet metal separated from one another by a filling of heat insulating material, reinforcing collars interposed between said cylindrical walls at the ends thereof, the lower collar being adapted to rest upon a suitable supporting surface for the cooker means carried by the lower collar to engage and be secured to a floor or other surface, a heat insulated cover hingedly connected to the upper collar, and said upper collar having an inwardly projecting supporting flange, a normally closed opening in the side wall of the cooker adjacent the base thereof, a liquid heating element bodily insertible and removable as a complete unit through said normally closed opening a cooking vessel arranged above said heating element having a flange at the upper edge thereof adapted to engage said flange of the upper collar, said cylindrical wall having an air opening adjacent the base thereof, and said supporting flange of the upper collar having air openings therein, means for maintaining the cover in a slightly elevated position, means for closing the air inlet, and means whereby when the cover is in closed position said air passages in said flange will be entirely closed to the outside.
6. In a fireless cooker, the combination of a casing comprising inner and outer walls, having therebetween a filling of insulating material, a reinforcing member interposed between said walls at the top and bottom thereof, the upper reinforcing member having an inwardly projecting member overlying the interior chamber formed by said casing, a cooking vessel in the chamber having an outwardly projecting member at its top resting upon said inwardly projecting member of the reinforcing member, a heating element confined within the cooker below the vessel, a movable top for the cooker, and movable means on the casing adapted according to its position to maintain said cover in either a raised or lowered position at will.
7. In a fireless cooker, the combination of a casing comprising inner and outer walls having therebetween a filling of insulated material, a reinforcing member interposed between said walls at the top and bottom thereof, the upper reinforcing member having an inwardly projecting member overlying the interior chamber formed by said casing, and a cooking vessel in said chamber, a heating member arranged within the cooker below the vessel, and said vessel having an outwardly projecting member at its top resting upon said inwardly projecting member of the reinforcing member.
8. In a fireless cooker, the combination of a casing comprising inner and outer walls having therebetween a filling of insulated material, a reinforcing member interposed between said walls at the top and bottom thereof, the upper reinforcing member having an inwardly projecting member overlying the interior chamber formed by said casing, and a cooking vessel in said chamber, said vessel having an outwardly projecting member at its top, resting upon said inwardly projecting member of the reinforcing member, said inwardly projecting member having a series of air openings, and a heating member positioned below said cooking vessel and bodily insertible and movable as a unit through the side wall of the cooker without disturbing said vessel.
9. In a fireless cooker, the combination of a casing comprising inner and outer walls having therebetween a filling of insulated material, a reinforcing member interposed between said walls at the top and bottom thereof, the upper reinforcing member having an inwardly projecting member overlying the interior chamber formed by said casing, a cooking vessel in said chamber, said vessel having an outwardly projecting member at its top, resting upon said inwardly projecting member of the reinforcing member, said inwardly projecting member having a series of air openings, a movable cover for said casing and means for maintaining the same in open position whereby the products of combustion may freely escape from said opening, said casing having an open bottom surrounded by the adjacent reinforcing member, and a removable heating element positioned in the bottom opening and supported interiorly of said casing.
10. In a fireless cooker, the combination of concentric cylindrical walls having an interposed filling of heat insulated material, rings or collars interposed between said walls at the top and bottom thereof, a cover hingedly connected to the upper collar, said upper collar having an inwardly projecting annular

series of segmental supporting flanges forming intermediate spaces for the passage of products of combustion, a cooking vessel having an annular bead at its upper edge supported, on said flanges, and a portable heat transmitting member within the casing below said vessel, said last mentioned member being bodily removable as a complete unit,

and means within the cooker for supporting said member in position. 10

In testimony whereof I hereunto affix my signature in the presence of two witnesses.
